UNITED STATES PATENT OFFICE.

GUY BENNETT WAITE, OF NEW YORK, N. Y.

FIREPROOF BUILDING STRUCTURE.

SPECIFICATION forming part of Letters Patent No. 755,336, dated March 22, 1904.

Application filed July 27, 1903. Serial No. 167,170. (No model.)

To all whom it may concern:

Be it known that I, GUY BENNETT WAITE, a citizen of the United States, residing at New York, in the county and State of New York, have invented certain new and useful Improvements in Fireproof Building Structures, of which the following is a specification.

My invention relates to fireproof building structures and methods of erecting the same, and more particularly to floor and ceiling structures of that type wherein are employed concrete or similar fireproof arches disposed at intervals transversely of and between the main-floor girders (which are usually steel I-beams) and constituting, with the latter, the supporting and carrying framework of the floor and ceiling coverings. Heretofore such arches in floor and ceiling work have generally been cast in place on and by means of temporary underlying centering, which latter is allowed to remain until the permanent supports have dried out and "set," after which the temporary centering is removed. Numerous considerations have established the desirability of replacing this slow and expensive method of construction by the employment of "ready-made" slabs or lintels. The latter can be made in a factory during winter or other unfavorable weather and involve less labor and expense in their manufacture; but, on the other hand, a difficulty which has been experienced in rendering the use of factory-made slabs and lintels practical has been the virtual impossibility of making the slabs exactly fit in between the steel floor-beams, the latter being in practice irregular in spans. It is not practical to cut the slabs to make them fit, and the exact fitting of the arches between the steel floor-beams forms a necessary factor in the construction. The only way heretofore found, so far as I am aware, to make the use of such factory-made slabs or lintels practical has been to cut the slabs of a uniform length slightly short of the minimum distance required to be spanned thereby and then fill in the space between one or both ends of the slab and the floor beam or beams, such space requiring to be filled in varying more or less, according to the spacing of the beams. Where this has been, however, temporary centering has been required to support the ready-made

slab during the introduction and "setting" of the end filling, or in lieu of the latter it has been proposed to supply the concrete slab or flag with iron strengthening strips, rods, or bars embedded therein and at their ends overlying and resting on the tops of the floor-beams and permanently supporting the slab or flag and its load, such spaces as may remain between the ends of endwise adjacent slabs and the floor-beam being filled in with concrete to bond the structure and enhance its finished appearance.

My present invention has for its principal object to render practical the use of factory-made slabs or lintels made in standard lengths in the manufacture of fireproof arches without requiring the use of either temporary centering therefor or permanent supports embedded therein; and this object I carry out through the novel expedient of suspension devices incorporated therein and carried over the floor-beams in association with end filling so applied as to constitute the permanent support of the slab and its load, said suspension devices, while they may be allowed to remain as a permanent part of the arch structure, nevertheless having as their function merely to support the weight of the slab or lintel while the filling or leg of the arch is setting, and so take the place of the usual centering employed beneath such slab or lintel. The slab may rest on the beam at one end and have the suspender on the other end only.

My invention also contemplates the employment in a floor-arch construction of concrete or similar slabs or lintels each characterized by the provision of a rib or web which rises to a height above the tops of the floor-beams and supports the floor construction, thereby raising the latter above all obstructions (such as a specially high girder in the floor or pipes of any kind) and dispensing with the filling which ordinarily has to be put in to raise the floor construction over such obstructions. For this purpose the use of factory-made slabs cut sufficiently short to lie between the top flanges or heads of the I-beam floor-girders, in association with end filling, is specially convenient and expedient.

In the accompanying drawings I have illustrated my invention as embodied in several

forms of concrete or similar floor-arches employing ready-made slabs or lintels.

Referring to the drawings, Figures 1 and 3 are side elevations of floor-arches embodying my invention, both employing flat factory-made slabs disposed between the lower and upper parts of the floor-beams, respectively, the latter appearing in section, and Fig. 1 showing what is known as a "flat" arch. Figs. 2 and 4 are cross-sectional views on the line 2 2 and 4 4 of Figs. 1 and 3, respectively. Fig. 5 is a perspective view of a section of complete floor and ceiling construction, showing more particularly that feature of my invention which finds its expression in arches that rise to a level above the level of the tops of the floor-beams. Fig. 6 is a top plan view of the construction shown in Fig. 5, with the floor construction removed. Fig. 7 is a cross-sectional detail view of one of the arch-beams shown in Figs. 5 and 6, and Figs. 8, 9, 10, and 11 are cross-sectional detail views of different forms of arch-beams, lintels, or slabs which may be employed within the spirit and purview of my invention.

Referring to the drawings, A designates each of a pair of floor-girders herein shown as having the form of a pair of steel I-beams.

B designates a shop or factory made slab or lintel constituting the principal member of the floor-arch. This slab may be cored, as shown at a, for the sake of lightness and has preferably embedded therein, as shown, a pair of suspension-wires b b. The slab is cut somewhat shorter than the space between the girders A, and the ends of the wires b b project from the end or ends of the slab and are carried up and hooked over the top flanges of the floor-girders, as shown. Temporary centering (partially indicated at C) is put in place between and beneath the lower flange of each girder and the adjacent end of the slab, and concrete or other end filling D is put in either before or after the slab is put in place to fill out the ends of the shop-made slab onto the lower flange of the girder and against the web of the latter, it being observed that the ends of the slab are cut obliquely, so as to wedge the latter between and cause it to be supported by the end fillings when the latter have become hard and set.

Figs. 3 and 4 show a solid slab or lintel B' slung from the tops of the floor-girders by suspenders b' b', the slab in this instance being positioned between the upper portions of the floor-girders. Here C indicates a part of the temporary centering to support the concrete end filling, D' constituting the leg of the complete arch, such end filling engaging the web and inner surfaces of the flanges of the floor-girder and filling the space between the latter and the end of the slab B', forming a permanent foundation and support for the latter.

Figs. 5, 6, and 7 illustrate the same prin-

ple or method in the construction and erection of the floor-arch as already disclosed, carried out, and embodied in a complete floor construction. Here A designates the same floor-girders as in the preceding figures, and B² designates the beams or lintels, which have the cross-sectional form shown in Fig. 7. It will be observed that the central vertical ribs of these beams are made of a height which may carry their upper margins above the tops of the floor-girders A. At b² are indicated the embedded wire suspenders by which the beams are supported for construction purposes from the floor-girders. If desired, and as indicated in Figs. 5 and 6, the beams, which are located side by side in close juxtaposition, may be stepped at one end on the base-flange of the floor-girder, thus dispensing with the necessity of temporary centering under the end filling at that end. D² designates such concrete end filling which completes the arch, giving it a perfect fit and support on its ends on the floor-girders. Supported directly on and across the ribs of the arch-beams B² is the metal lath E, while running diagonally over said ribs above the metal lath are sleepers F F' F², on which latter is laid the flooring G, a filling H being interposed between the lath and flooring and embedding the sleepers. I designates the ceiling-plaster beneath the arches and floor-beams. K designates pipes laid crosswise of the ribs of the arches directly beneath the metal lath, for the accommodation of which pipes said ribs are notched, as shown at m, and L designates other pipes disposed parallel with and between the ribs and resting across the tops of the floor-girders.

Among the advantages presented by the last-described construction may be mentioned the fact that the ribs can be made of this increased height without materially increasing the weight of construction, while they raise the floor construction above all obstructions, (such as a specially high girder in the floor or pipes of any kind,) and thus save the filling which has to be put in ordinarily to raise the floor construction over such obstructions. They also produce a stronger and lighter structure than any other with which I am acquainted.

Figs. 8, 9, 10, and 11 are intended to illustrate still others out of a great variety of forms which the arch beams or lintels may take when employed in carrying out my invention. In Fig. 8 the beam B³ is I-shaped in cross-section and has its suspender b³ embedded, preferably, in its lower portion. Fig. 9 shows a beam B⁴ of T shape in cross-section, being an inversion of the form shown in Figs. 5 to 7 and carrying its suspender b⁴. Fig. 10 shows a plain vertical beam or slab B⁵, carrying in its lower end its suspending-wire b⁵, and B⁶ in Fig. 11 represents a cored horizontal slab or beam substantially like that shown in Figs. 1 and 2 and having a single central sus-

pending-wire b^6 . It is entirely evident that still other forms of beams or lintels might be employed in the construction of my improved arch, the particular form of such beam or lintel not being material so far as concerns the described means and manner of support.

It will thus be seen that by my present invention I make possible and practical the use of shop-made slabs or lintels cut to standard or stock lengths in an economical way, since I dispense entirely with the necessity of temporary centering for the ready-made part of the arch and also do not employ or require any permanent supports for the latter, which are expensive, and by permanent supports I mean supports such as are designed to and do support not only the weight of the arch-beam during construction, but also the weight of whatever load or loads the finished floor is subsequently required to carry. The wire or other suspenders $b^1 b^2 b^3$, &c., such as I employ, are not a necessary element of the finished construction, but merely a temporary support until the end fillings or fillings have set and are able to carry the arch and its load, although such suspenders may and preferably will be allowed to remain during and after the completion of the structure. With my invention no temporary centering for the arch is required beyond merely enough to support the end fillings or beddings for the factory-made materials, such as I have indicated at C and C', and this can be soon removed, since the suspenders carry the weight of the arch-beam during construction, which suspenders can also, if desired, be made to also form the suspension means for the temporary centering of the end fillings. This enables the work of construction to proceed rapidly and with much greater expedition than by the present method, almost universally employed, of casting the entire arch in place on temporary centering, which has to be left standing until the arch has become self-supporting. The saving in time involved in the manufacture of the arch-beams, slabs, or lintels in shops and factories during winter and other unseasonable times when outdoor-building operations are necessarily suspended is another marked advantage resulting from the use of my invention.

I claim—

1. In a fireproof structure of the character described, the combination of a shop-made arch beam or lintel and suspenders slinging it from the floor-girders, said arch-beam being supplemented by concrete or the like cast in at one or both ends to fill it out to and against the floor-girders in such a manner as to resist the vertical strains through the arch, substantially as described.

2. In a fireproof structure of the character described, the combination with a shop-made

arch beam or lintel cut or molded to a stock length and one or more wire suspenders embedded therein longitudinally thereof and projecting from its ends whereby it may be slung from the tops of the floor-girders, of a supplemental concrete filling or bedding cast in at one or both ends of said arch-beam and filling it out to and against the floor-girders in such a manner as to resist the vertical strains through the arch, substantially as described.

3. In a fireproof structure of the character described, the combination with the floor-girders, of arch-beams extending transversely of and between adjacent floor-girders, said arch-beams extending to a height above the level of the tops of the floor-girders and being stepped at one end directly on the lower flange of one floor-girder and supported at the other end by the lower flange of the other floor-girder through an interposed filling of concrete or the like, substantially as described.

4. In a fireproof structure of the character described, the combination with the floor-girders, of arch-beams of inverted-T shape in cross-section disposed transversely of and between adjacent floor-girders, said arch-beams each having its vertical rib or web extended to a height above the tops of the floor-girders and being stepped at one end directly on the lower flange of one floor-girder and supported at the other end by the lower flange of the other floor-girder through an interposed filling of concrete or the like, substantially as described.

5. In a fireproof structure of the character described, the combination with the floor-girders, of shop-made arch beams or lintels cut in stock lengths disposed between adjacent girders, each of said arch-beams having a vertical rib or web and being further provided with suspenders embedded therein longitudinally thereof by which it is slung over the tops of the floor-girders and supported therefrom during construction, and concrete or the like cast in at one or both ends of said arch-beam and filling it out to and against the floor-girders in such a manner as to support the vertical strains through the arch, substantially as described.

6. The herein-described method of erecting fireproof structures which consists in cutting or molding to standard or stock lengths factory-made arch-beams, slabs, or lintels, suspending the latter from and between the floor-girders during construction, and molding in place an end filling of concrete or the like to fill out the end of the factory-made beam to and against the floor-girder and to support the vertical strains through the arch, substantially as described.
